UNITED STATES PATENT OFFICE.

ROBERT EMIL FELDGES, OF NEW YORK, N. Y.

MECHANICAL MOVEMENT.

SPECIFICATION forming part of Letters Patent No. 368,083, dated August 9, 1887.

Application filed September 9, 1886. Serial No. 213,112. (No model.)

To all whom it may concern:

Be it known that I, ROBERT EMIL FELDGES, a subject of the King of Prussia, residing at New York, in the county and State of New York, have invented new and useful Improvements in Mechanical Movements, of which the following is a specification.

The object of this invention is to provide a mechanical movement capable of delicate adjustment and accurate working; and I accomplish this object by means of the device set forth in the following specification and claims, and illustrated in the accompanying drawings, in which—

15 Figure 1 is a side elevation of my mechanical movement. Fig. 2 is a section in the plane $x x$, Fig. 1.

Similar letters indicate corresponding parts.

A is a frame, of iron, wood, or other suitable 20 material. In this frame is suitably mounted a shaft or axle, B, on which turns a ratchet-wheel, C. The ratchet-wheel C is actuated or turned in the direction of arrow 9 by a driving arm or lever, D, swinging on the shaft B. A driving-pawl, E, is hinged or suitably attached to the arm D. A spring, F, is attached to the arm D and holds the driving-pawl in engagement with the ratchet-wheel. The ratchet-wheel C is provided with teeth, a portion of 25 said teeth being indicated in the drawings by the numbers 1 to 8.

The driving-pawl E is provided with teeth $a b c d$, adapted to engage with the teeth on the ratchet-wheel C. The pawl-teeth $a b c d$ are arranged in suitable ways or guides in the driving-pawl. The driving-pawl is pressed upon by a spring, F, and springs a^2 are applied to force said teeth $a b c d$ into engagement with the teeth of the ratchet-wheel C. The 30 pawl-teeth $a b c d$ are fractionally or differentially arranged in relation to the ratchet-wheel teeth—that is, for example, as shown in the drawings. When the pawl-tooth a is in engagement with the driving-gear tooth 1, a movement of the driving-pawl E in the direction opposed to that of arrow 9, and through a distance equal to a fractional part of the length of a ratchet-wheel tooth, will bring the pawl-tooth b into engagement with the ratchet-wheel tooth 2. A movement of the driving-pawl E in the direction opposed to that of arrow 9, and through a distance equal to an-

other fractional part of the length of a ratchet-wheel tooth, will bring the pawl-tooth c into engagement with the ratchet-wheel tooth 3. 55 By thus fractionally or differentially arranging the pawl-teeth $a b c d$ in relation to the ratchet-wheel teeth one pawl-tooth will always be brought into engagement with a ratchet-wheel tooth, and the driving-pawl will actuate the ratchet-wheel even if the oscillations of the driving-pawl should be through a less or smaller distance than the length of one of the ratchet-wheel teeth. If desired, the driving-pawl E can thus be made to impart a slow 60 motion to the ratchet-wheel.

A stop-pawl, G, is hinged or suitably attached to the frame A, and prevents retrograde motion of the ratchet-wheel. A spring, H, presses upon the stop-pawl G, and the latter is provided with sliding pawl-teeth $e f g h$, 70 acted on by springs a^3 . The stop-pawl teeth $e f g h$ are also fractionally or differentially arranged in regard to the ratchet-wheel teeth, as already explained in relation to the driving-pawl teeth, so that, for example, as shown 75 in the drawings, the stop-pawl tooth e , being in engagement with the ratchet-wheel tooth 5, one of the stop-pawl teeth $f g h$ will be brought into engagement with one of the ratchet-wheel teeth 6, 7, or 8, as the ratchet-wheel moves through distances equal to varying fractional parts of the length of a ratchet-wheel tooth. The stop-pawl G is thus always enabled to prevent retrograde motion of the ratchet-wheel by one of the stop-pawl teeth $e f g h$ engaging one of the ratchet-wheel teeth, even if the motion of the ratchet-wheel be through a less or smaller distance than the length of a ratchet-wheel tooth. The oscillations of the 80 driving-arm D and driving-pawl E about the axle or shaft B impart motion to the ratchet-wheel C.

To limit or regulate the oscillations of the driving-arm D, I provide a regulator, I. This 95 regulator I consists of a suitable surface, either plane or curved, with which the driving-arm comes into contact, thereby arresting or stopping the motion of the driving-arm in one direction. In the example shown in the drawings the regulator consists of a plane hinged at J to a base or support, L, said plane being held in an inclined position by an upright or arm, K. By providing the arm K with a

screw-thread and with nuts *i* the inclination of the plane or surface can be varied and adjusted as desired. The base or support *L* of the regulator *I* is adapted to slide or travel in a suitable guide or way, *M*, in the floor or in a base-plate of the mechanism.

When the lower part of the regulator *I* is in proximity to the arm *D*, the arm *D* is free to oscillate through a considerable space and to impart considerable movement to the ratchet-wheel. As the regulator is moved to bring the higher part of the regulator *I* to the arm *D*, the motion of the arm *D*, and consequently of the ratchet-wheel *C*, is diminished. The regulator *I* thus enables the motion of the ratchet-wheel *C* to be adjusted or controlled as desired. To soften the contact between the arm or lever *D* and the regulator *I*, a cushion or pad, *j*, of suitable soft or elastic material—such as leather—may be applied to the arm *D*.

In the example shown in the drawings the regulator *I* is automatically actuated. The ratchet-wheel *C* has connected to it a gear, *N*, and by a train of gears, *O P Q R S*, motion is imparted to the shaft or axle *m*, connected to the gear *S*. An arm or pawl, *T*, is connected to the shaft *m*, and every revolution of the pawl *T* revolves the gear-wheel *U* a certain distance in the direction of arrow 10. To the axis of the gear-wheel *U* is attached a bevel gear-wheel, *W*, gearing into a bevel gear-wheel, *X*. As the gear *U* is revolved in the direction of arrow 10 the bevel-wheel *X* and its shaft *Y* and the gear-wheel *Z* are revolved in the direction of arrow 11. The gear-wheel *Z* is connected to the shaft *Y*, or mounted on said shaft, and said gear-wheel *Z* engages with a gear-wheel, *p*, which in turn engages with a rack, *l*, on the regulator. As the gear *p* is revolved in the direction of arrow 12 the regulator is moved in the direction of arrow 13, bringing the higher part of the regulator into proximity with the arm *D* and gradually diminishing the movements of the arm or lever *D* and of the ratchet-wheel.

The gears *O P Q R S U* are suitably mounted in the frame of the device, and the shaft *Y* and gear *p* are suitably mounted or supported on the floor or base of the device. A stop-pawl, *V*, suitably pivoted or mounted, prevents retrograde motion of the gear *U*.

To return the regulator *I* to its starting-point, it is only necessary to disengage the stop-pawl *V* from the gear *U*, when the regulator *I* can be moved by hand to the position desired; or by connecting the gear *U* with a weight or spring, *o*, which is wound up by the revolution of the gear *U*, said spring or weight, upon the disengagement of the stop-pawl *V*, will automatically return the regulator *I* to its starting-point. In the drawings I have indicated a coiled spring, *o*, one end of which is attached to the frame of the device and the other end to the axle of the gear *U*.

In the drawings the driving arm or lever *D* is shown as being actuated by a cord or chain, *q*, to which cord or chain a suitable oscillating

motion is imparted. The cord or chain *q* is connected to a hook or eye, *r*, on the driving-arm *D*. Said hook or eye *r* can be adjusted or moved to various positions along the driving-arm *D* by a screw, *s*, actuated by a finger-button, *t*, and when the proper position of the hook or eye *r* has been ascertained the revolution of the screw *s* can be stopped by a set-screw, *u*. Said screw *s* engages a nut, *r'*, of the hook *r*. The action of the cord or chain *q* on the driving-arm *D* can thus be adjusted or regulated.

I have found it advantageous to supply means for lengthening or shortening the cord *q*. In the drawings is shown an eye or hook, *c*, engaging the hook or eye *r*. The eye *c* is provided with a frame or guide, *d*, having a recess for a finger-button, *f*. The finger-button *f* is tapped for the passage of a screw-shank, *e*, having a hook or eye, *b*, to which the cord or chain *q* is attached. A proper motion of the finger-button *f* will cause the screw-shank *e* to be moved so as to secure the proper relation of the cord *q* to the driving-arm *D*.

In the drawings I have shown an example of my mechanical movement applied to a loom, the letter *w* indicating an oscillating arm—as, for example, the batten of a loom—to which the cord *q* is attached, and from which batten the cord receives motion as said batten oscillates. This motion of the cord *q* oscillates the driving-lever *D* and revolves the train of gears. The shaft *m* of the gear *S* serves as the take-up or cloth-beam, on which the woven or finished cloth or fabric from the shed *w* is wound. As more cloth is wound on the cloth beam or shaft *m*, the diameter of the roll of cloth becomes greater, and if the cloth-beam *m* revolved continually at the same speed the circumference of the cloth-roll, as said roll increases, would acquire greater speed; but since by my mechanical device the regulator *I* gradually diminishes the action or throw of the lever *D*, the circumferential speed of the cloth beam or shaft *m* is diminished as the diameter of the cloth-roll is increased, so that by a proper adjustment and construction of the parts the cloth-roll can always be caused to turn at a fixed circumferential speed, thus avoiding any breakage or injury in the operation of weaving.

Of course I do not confine myself to the application of my mechanical movement to a loom, but I mention a loom as a mechanism in which my movement can be advantageously employed. I can, for example, also employ my movement in such apparatus as paper-mills, in case it is desired to roll up finished paper at a uniform speed.

The arm or pawl *T* is adjustably connected to or mounted on the shaft *m*, and can be fixed in position by a set-screw, *n*. Said pawl *T* can thus be adjusted to properly engage with the gear *U*. If it is desired to stop the motion of the gear *U*, and consequently of the regulator *I*, it is only necessary to slide or

move the arm T into such a position that no engagement of the arm or pawl T and of the gear U takes place. The gear U and the bevel-gears W X, with the shaft Y, constitute an actuating mechanism for the regulator I, and

5 by connecting said actuating mechanism to the ratchet-wheel C, as shown in the drawings, said actuating mechanism receives motion only as the ratchet-wheel is actuated.

10 What I claim as new, and desire to secure by Letters Patent, is—

15 1. The combination of the ratchet-wheel C, the driving-arm D, the driving-pawl E on the arm, the teeth on the pawl, the regulator, comprising a horizontally-sliding base L, an incline hinged at one end to the base, and devices for raising and lowering the other end of the incline, and gearing connecting the ratchet-wheel with the said base for advancing the 20 regulator to diminish the downward throw of the driving-arm, substantially as described.

25 2. The combination of the ratchet-wheel C, the driving-arm D, the driving-pawl E on the arm, teeth on the pawl, the regulator, comprising the sliding base L, having a rack, the incline hinged at one end to said base, and means for raising and lowering the other end of the incline, and gearing, substantially as described, connecting the ratchet-wheel with the rack on 30 the base for advancing the regulator to diminish the downward throw of the driving-arm, for the purposes set forth.

35 3. The combination, with the ratchet-wheel C, driving-arm D, and driving-pawl E, of the gears N O P Q R S, a pawl, T, secured to and revolving with the shaft of the gear S, the gear-wheel U, actuated by said pawl, the bevel gear-wheels W X, the vertical shaft Y, having the gear-wheel Z at its lower end, the regulator

I, having a rack, l, in gear with the gear-wheel at the lower end of the vertical shaft for advancing the regulator to diminish the throw of the driving-arm, substantially as described.

4. The combination, with the ratchet-wheel C, driving-arm D, and driving-pawl E, of the regulator I, comprising a sliding base, L, having a vertical screw, K, an incline hinged at one end to said base, and connected at its other end with the screw-nuts i k on the screw for 50 raising and lowering one end of the incline, and gearing connecting the ratchet-wheel with the sliding base for advancing the regulator to diminish the throw of the driving-arm, substantially as described.

5. The combination of the driving-arm D, the cord q, the adjustable connection r, screw s, and setting device u, with the ratchet-wheel and the driving-pawl, and teeth on said pawl arranged fractionally in relation to the ratchet-wheel teeth; substantially as herein set forth.

6. The combination, with a reciprocating body, w, of a driving-arm, D, a cord or chain connecting said body and arm, a driving-pawl, E, on the latter, a ratchet-wheel, C, a regulator, I, comprising a sliding base, L, a hinged incline and means for adjusting the incline, and gearing, substantially as described, connecting the ratchet-wheel with the sliding base of the regulator, substantially as described.

In testimony whereof I have hereunto set my hand and seal in the presence of two subscribing witnesses.
